DESIGN FOR A DRESS

Charlotte Flusser, New York, N. Y.

Application April 8, 1939, Serial No. 84,139

Term of patent 3½ years

To all whom it may concern:

Be it known that I, Charlotte Flusser, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

Fig. 2 is the rear view thereof.

The characteristic feature of my design resides in the combination on the specific dress disclosed of the specific embroidered bands separated by rows of embroidered eyelets arranged on the skirt and blouse as shown.

I claim:

The ornamental design for a dress, substantially as shown and described.

CHARLOTTE FLUSSER.
